United States Patent Office

Des. 221,665
Patented Aug. 31, 1971

221,665

SPEAKER ENCLOSURE

Yoshiaki Iida, Neyagawa, Osaka, and Noboru Shiroasaki,
Amagasaki, Japan, assignors to Matsushita Electric In-
dustrial Co., Ltd., Osaka, Japan

Filed May 6, 1970, Ser. No. 22,864

Term of patent 14 years

Int. Cl. D14—01

U.S. Cl. D26—14

FIG. 1

FIG. 2

FIG. 3

FIG. 1 is a front and left side perspective view of a speaker enclosure showing our new design,

FIG. 2 is a right side elevational view thereof, and
FIG. 3 is a top plan view thereof.

The rear view is a mirror image of the front view.

We claim:

The ornamental design for a speaker enclosure, as
shown and described.
